HOLLANDER

Fritz Arledter, Cologne-Kalk, Germany

Application December 21, 1932, Serial No. 648,202
In Germany July 4, 1932

9 Claims. (Cl. 92—25)

The present invention relates to hollanders and more particularly to an improved vacuum hollander.

It is an object of the invention to provide a vacuum hollander which is capable of saving approximately 25% of power by reducing and/or avoiding friction and by the elimination of air in the pulp.

It is another object of the invention to provide a vacuum hollander which relieves the rotating roll or cylinder from the burden of lifting pulp to a substantial extent extending up to about 76% or 78%.

A further object of the invention is to provide a vacuum hollander having an increased production up to about 20% with the same capacity of hollander trough and saving up to about 30% in time of grinding, coloring, liming or bleaching.

Another object of the invention is the provision of a vacuum hollander capable of increasing the density of the pulp up to about 22% and of providing good viscousness, bleaching and hydration in pulp.

It is also within the contemplation of the invention to provide a vacuum hollander producing a substantially uniform mixture of paper pulp and a substantially uniform speed of circulation of pulp through the hollander trough.

The invention also provides a vacuum hollander which is substantially silent in operation, which has greatest cleanliness and which has no dead corners.

Still another object of the invention is to provide a vacuum hollander which gives practically a complete mixture with only one course through the hollander, which is suitable for continuous function or operation in conjunction with a rotary press and which functions in substantially a foamless manner within the hollander and on the paper-making machine.

The invention likewise provides a hollander which effects a saving in machine materials, bed plate, cylinders or rolls, knives, disks and the like and which causes a self-cleaning of the paper pulp and prevents particles of metal, iron and the like from reaching the milling or grinding parts.

Other objects and advantages will become apparent from the following description taken in conjunction with the drawings in which

Figs. 1, 2 and 3 are diagrammatic views of preferred embodiments of the invention; and

Fig. 4 is a sectional view in detail of a vacuum hollander embodying the principles of the present invention; and

Fig. 5 is a sectional view of Fig. 4.

A preferred type of hollander embodying the principle of the present invention is illustrated in Fig. 1. In this figure the reference character A designates the casing of the hollander which may be cylindrical or ball shaped. In either case, the sides are flat as one skilled in the art will readily understand. With hollanders of this type, it has been found that the pulp or substance under treatment will be thoroughly and intensively mixed to produce an even and uniform mixture.

It will be observed that grinding cylinder or roll B revolves in a trough T. Directly under the roll two bed plates E are provided. One bed plate is mounted within trough T at the entrance of mouth F—1, while the second bed plate is mounted underneath the roll and adjacent to a second mouth F—2. From the bed plates, the material under treatment passes through a channel K between the outside of grinding roll B and the inside of trough T. The channel leads into a funnel X which is mounted at the top of trough T and in connection with the body of the liquid within casing A. This body of liquid is acted upon by a vacuum via connection V.

As in the foregoing hollanders the feed is introduced through inlet pipe O. The feed passes through the mouths associated with the bed plates and is carried along by cylinder B. When the vacuum is applied, the material is drawn up and flows over the top edge of the funnel X, thus establishing a circulation.

It is to be noted that the pulp or material under treatment is drawn up from below the grinding cylinder or roll and is thrown off above it. The cylinder does not wade in the pulpy mass and there is no friction between the left surface of the grinding roll and the wall of the trough. In this manner, a substantial saving of power can be effective and in some instances a saving in power up to about 50% has been accomplished. In addition, the lifting of the material is effected primarily by the vacuum which relieves the grinding cylinder of more than two-thirds of its work. Consequently, an additional saving in power is made by this effect.

In Fig. 2 another embodiment of the invention is illustrated. In this form of hollander casing A has an irregular egg shaped form. Grinding roll B is placed somewhat to the left of casing A and is mounted in trough T. A bed plate is located underneath roll B and adjacent to mouth F. At the outlet of channel K and adjacent to funnel X is a second bed plate E.

Inlet O introduces the feed to the hollander and a circulation is established as indicated by the arrows. Above the body of the circulating liquid a vacuum is maintained by means of a vacuum connection V leading to an appropriate vacuum pump, or the like.

A further modification is shown in Fig. 3 in which casing A has a more or less sphere-like shape. Within the casing A a grinding cylinder or roll B is mounted adjacent to the bottom thereof. Underneath grinding roll B a bed plate E is provided. A mouth F leads to the space between the bottom of the grinding roll B and the wall or casing A. Above the grinding roll a trough like cover T-1 is provided. This trough like cover extends from a region adjacent to mouth F to a region over the right-hand upper side of the grinding roll. To the left of the grinding roll, a trough T-2 is provided.

When a vacuum is applied to the space above the body of liquid within casing A by means of a vacuum pump connected via connection V and when grinding roll B rotates in the direction indicated by the arrow, a circulation of pulp is set up as indicated by the arrows. It will be observed that inlet O introduces the feed in the left-hand side of the casing in a region where the circulation is flowing downwardly to mouth F as indicated by the arrows.

An embodiment of the invention which has been found to be preferable for commercial and industrial use is illustrated in Figs. 4 and 5. It will be noted from Fig. 4 that the general form of the hollander is somewhat similar to the embodiment illustrated in Fig. 3.

Casing A is made in the form of a ball or sphere. It is preferred to make the casing of two castings. The lower half of the casing constitutes one casting while the upper half of the casing constitutes the second casting. These castings may be secured together in any appropriate manner. For instance, a plurality of bolts such as indicated in the drawings may be used for securing the two castings together to form casing A. Of course, a gasket or the like may be interposed between the two castings.

In the upper casting a cover N is provided. This cover is secured to the casing in any appropriate manner such as by means of a plurality of studs and thumb screws 1. The cover is preferably provided with a glass window or some other transparent material so that the operator of the hollander can look through the same and see how the material is being ground. In addition to cover N, a connection V is provided at the top of the casing. This connection is connected to a vacuum pump or other appropriate means for creating a vacuum within the casing.

Mounted in the lower part of the casing is a grinding cylinder or roll B provided with a plurality of knives or blades 2. The grinding or milling roll of iron metal or stone is carried on a shaft 3 which is supported by a standard 4 on each side of casing A as may be seen from Fig. 5. Shaft 3 is rotated in any appropriate manner as by means of a pulley 5.

Surrounding a substantial part of grinding roll B is a trough T'. In the present instance, the trough T' has an adjustable tongue 6 mounted on the upper side thereof. Of course, the lower end of trough T' can likewise be provided with an adjustable tongue, if desired. Below the lower end of trough T' is a mouth F leading to the grinding roll. At the bottom of the casing and in this instance, directly below mouth F is a dis-

charge outlet 7 which is provided with a manually operated gate 8 for discharging the contents of the hollander.

Within the lower right-hand part of the casing, a housing 9 is provided. Within this housing a bed plate 10 is mounted with a plurality of blades or knives 11 or stones. As one skilled in the art will readily understand, blades 11 in bed plate 10 coact with blades 2 of grinding roll B to disintegrate the fibers or other material being treated in the hollander.

For the convenience of the operator, a port 12 is provided in the upper part of casing A above the grinding roll to permit the operator to inspect the interior of the casing. In this manner, an operator can closely watch the progress of the procedure being carried out in the hollander and make any observations which he cares to.

On the left-hand upper side of the casing, a lug co-acts with an adjustable arm 14 having a plurality of holes 15 in the upper end thereof. The lower end of arm 14 is pivoted to a fixed support 16. The casing A may be adjusted to any desired height by passing bolt 17 through the desired hole 15.

The operation of the hollander will be obvious to anyone skilled in the art. The hollander is set at the proper angle by making an appropriate adjustment with arm 14. A connection is made to a vacuum pump by means of connection V. Cover N is removed and a charge of material is introduced into the casing. This charge may be paper pulp consisting of a fibrous material carried in water. Of course, any other appropriate type of material can likewise be treated. Grinding roll B is rotated in a direction indicated by the arrow. A vacuum is then applied and the space above the top of the liquid is evacuated. The fibrous pulp enters the mouth F and is then drawn between the blades of the grinding roll and the blades of the bed plate. The ground fibers are thrown in a stream substantially tangential to the periphery of the grinding roll. This stream is directed upwardly within the casing. When the fibers reach the upper portion of the body of liquid within casing A, they are deaerated by means of the vacuum. In this manner, the deaeration of the fibers and the subsequent hydration thereof are facilitated. The operator can observe the progress of the treatment through the port or peep hole 12. When the operation is complete the vacuum may be shut off and the rotation of grinding roll B may be discontinued. The content or charge of casing A may be discharged by moving gate 8 into the position shown in Fig. 6. In this position the material in the casing will be discharged through discharge outlet 7.

It will be observed that the present invention provides a hollander or beater which can be used to good advantage in the paper and pulp industry and in addition to other industries. For instance, in view of the extraordinary hydration effects obtained by the present hollander or beater, it is possible to produce colloidal cellulose under very economical conditions. On drying such colloidal cellulose, it is possible to produce blocks or slabs which can be formed into a number of useful articles. Thus, for example, these blocks or slabs may be employed in the production of boards, panels, etc. and especially asbestos boards, and the like. In addition, the hollander may be employed in conjunction with the production of nitro-cellulose explosives, the production of alcohol from vege-

table matter, particularly tropical vegetation. Moreover, the hollander or beater can be used for a great variety of other uses, in particular it may be pointed out that the present hollander is especially useful in the dehydration of peat; in the washing of wool; in the manufacture of imitation leather; in the production of briquettes; in the preparation of cork for linoleum, etc.; in the distillation of petroleum; in the treatment of saw-dust for the manufacture of insulating and sound-proof materials for ice boxes, refrigerators, pipe coverings, telephone booths; in the mixing of oils, colors, etc.; in the making of size for paper and textiles; in the preparation of foodstuffs; in the treatment of seaweed; and in the preparation of pulp for the manufacture of artificial silk. It will be further observed that the present invention provides a hollander or beater which can be used to advantage in processes wherein volatile chemicals are used instead of water and wherein such volatile chemicals can be recovered.

It is also to be noted that the present invention provides a hollander or beater in which the grinding or milling cylinder does not wallow or wade in the material under treatment in which clogging of the material in any part of the machine is practically impossible and in which the knives or blades are protected due to the fact that there is a depression adjacent to the mouth leading to the grinding or milling parts.

Furthermore, the present invention provides a hollander or beater in which the rising of the air contained in the material and fibers under treatment gives the mass of pulp in the riser pipe more speed and the higher the pulp rises the faster it moves, thereby decidedly increasing the speed of circulation and permitting the grinding or milling cylinder to run faster with a resultant better combing of the fibers without the necessity of using a strong pressure against the bed plate.

Although the present invention has been described in connection with certain embodiments thereof, it should be understood that variations and modifications may be resorted to without departing from the scope and spirit of the invention. For instance, the hollanders have herein been shown as being constructed in a vertical manner. It is to be understood that the hollander may be set at various angles or horizontally. Other changes may be made as one skilled in the art will readily understand.

I claim:

1. An improved hollander adapted to beat and disintegrate fibers which comprises a sphere-like closed casing, a grinding cylinder located at the bottom thereof, a trough surrounding the upper part of said grinding cylinder to provide an inlet mouth at the bottom and a discharge mouth at the top, a bed plate under said grinding cylinder, an inlet for introducing fibers to be beaten and disintegrated in said casing, an outlet for removing the beaten and disintegrated fibers, means for producing a vacuum in the casing, and means for driving said grinding cylinder.

2. An improved hollander adapted to beat and disintegrate fibers which comprises a sphere-like closed casing, a grinding cylinder having knives on the periphery thereof and located at the bottom thereof, a trough surrounding the upper part of said grinding cylinder to provide an inlet mouth at the bottom and a discharge mouth at the top, a bed plate under said grinding cylinder, an inlet for introducing fibers to be beaten and disintegrated in said casing, an outlet for remov-

ing the beaten and disintegrated fibers, means for producing a vacuum in the casing, and means for driving said grinding cylinder.

3. An improved hollander adapted to beat and disintegrate fibers which comprises a sphere-like closed casing, a grinding cylinder located at the bottom thereof, an adjustable tongue provided at the upper part of said trough, a trough surrounding the upper part of said grinding cylinder to provide an inlet mouth at the bottom and a discharge mouth at the top, a bed plate under said grinding cylinder, an inlet for introducing fibers to be beaten and disintegrated in said casing, an outlet for removing the beaten and disintegrated fibers, a connection for said casing to put the same under vacuum, and means for driving said grinding cylinder.

4. An improved hollander adapted to beat and disintegrate fibers which comprises a sphere-like closed casing, a grinding cylinder located at the bottom thereof, a trough surrounding the upper part of said grinding cylinder to provide an inlet mouth at the bottom and a discharge mouth at the top, a bed plate under said grinding cylinder, an inlet for introducing fibers to be beaten and disintegrated in said casing, an outlet for removing the beaten and disintegrated fibers, a connection for said casing to put the same under vacuum, means for driving said grinding cylinder including a shaft, and a pair of standards for holding said shaft.

5. An improved hollander adapted to beat and disintegrate fibers which comprises a sphere-like closed casing, a grinding cylinder located at the bottom thereof, a trough surrounding the upper part of said grinding cylinder to provide an inlet mouth at the bottom and a discharge mouth at the top, a bed plate under said grinding cylinder, an inlet for introducing fibers to be beaten and disintegrated in said casing, an outlet for removing the beaten and disintegrated fibers, a connection for said casing to put the same under vacuum, means for driving said grinding cylinder including a shaft, a pair of standards for holding said shaft, and driving means associated with said shaft to effect a rotation thereof.

6. An improved hollander to beat and to disintegrate fibers which comprises a sphere-like closed casing consisting of an upper member and a lower member, a grinding cylinder located in said lower member, a shaft passing through said grinding cylinder and said lower member, a pair of standards supporting said shaft and said casing, a trough provided surrounding the upper part of said grinding cylinder and extending close to the inner wall of the casing to provide an inlet mouth at the bottom of the grinding cylinder and a discharge mouth at the top of the cylinder, a bed plate underneath said grinding cylinder and positioned between said two mouths, an inlet for introducing fibers to be beaten and disintegrated, an outlet for discharging beaten disintegrated fibers, a vacuum connection for said casing, and driving means to actuate said cylinder and associated shaft.

7. An improved hollander to beat and disintegrate fibers which comprises a sphere-like closed casing consisting of an upper member and a lower member, a grinding cylinder located in said lower member, a shaft passing through said grinding cylinder and said lower member, a pair of standards supporting said shaft and said casing, a trough provided surrounding the upper part of said grinding cylinder and extending close to the inner wall of the casing to provide an

5 inlet mouth at the bottom of the grinding cylinder and a discharge mouth at the top of the cylinder, a bed plate underneath said grinding cylinder and positioned between said two mouths, an inlet for introducing fibers to be beaten and disintegrated, an outlet for discharging beaten disintegrated fibers, a vacuum connection for said casing, driving means to actuate said cylinder and associated shaft, and an arm secured to said casing for supporting the same.

10 8. An improved hollander to beat and to disintegrate fibers which comprises a sphere-like closed casing consisting of an upper member and a lower member, a grinding cylinder located in said lower member, a shaft passing through said grinding cylinder and said lower member, a pair of standards supporting said shaft and said casing, a trough provided surrounding the upper part of said grinding cylinder and extending close

5 to the inner wall of the casing to provide an inlet mouth at the bottom of the grinding cylinder and a discharge mouth at the top of the cylinder, a bed plate underneath said grinding cylinder and positioned between said two mouths, an inlet for introducing fibers to be beaten disintegrated fibers, a vacuum connection for said casing, and an adjustable arm secured to said casing for supporting the same in any desired adjusted inclination.

10 9. The process of beating, disintegrating and treating fibers which comprises establishing a body of fibers in water, causing a vertical circulation in said body, deaerating said fibers under a vacuum and grinding said fibers at the bottom 15 of said body under a static head, thereby hydrating the deaerated fibers.

FRITZ ARLEDTER.
